UNITED STATES PATENT OFFICE

2,452,462

CONCRETE EXPANSION JOINT

John N. Heltzel, Warren, Ohio

Application September 7, 1944, Serial No. 553,057

2 Claims. (Cl. 94—18)

1

This invention relates to dowel means for concrete expansion joints, or contraction joints.

The invention is more particularly concerned with improved dowel means for expansion joints as provided between concrete or similar slabs or sections of roadways, floors, airfield runways, walls, and the like, for permitting relative horizontal movement of the slabs, while preventing the same from shifting laterally and vertically of their planes; and the present application is a continuation in part of my copending application Serial No. 313,128, Patent No. 2,358,328, filed January 9, 1940.

Modern traffic conditions on highways and airfield runways have necessitated an increased use of load transfer members bridging joints, both longitudinal or transverse, between the opposed edges of adjacent concrete slabs. Experience has shown that the problem is not solved by the mere addition of load transfer dowels, such as commonly employed, for the shrinkage of plastic concrete when drying sets up a frictional drag on the embedded dowel bars, with the consequent breaking of the concrete at points remote from the joints between the slabs. It has been found, also, that where dowel bars alone are depended upon, there is an inevitable warping of the concrete slabs which tends to bend the dowel bars. This bending prevents restoration of the slabs to their initial condition on the subgrade and in addition, there is a constant breaking away of concrete or falling off of the material at the faces of the concrete slabs in the areas surrounding and adjacent to the dowel bars.

The tendency of adjacent concrete slabs and the joints between the slabs to shift under changing atmospheric conditions as well as under the incessant loads passing thereover has long been recognized, and the provision of efficient load transfer means at such joints has attracted the skill of engineers in many fields as well as steel and concrete contractors, and as a result many varieties of load transfer means in the form of dowels bridging concrete slab joint have been proposed and used.

In the use of such load transfer dowels, it is necessary of course that expansion and contraction of the joint be permitted as a result of which, the dowels must have relative movement to one of the slabs adjacent a joint in a direction axially of the dowels, and it is also essential that the dowels have relatively no movement transverse of their axes.

It has been found that dowels in use with concrete expansion joints, should for greatest efficiency be so united with at least one of the slabs as to remain rigid therewith under all conditions of use, and that such united dowels be confined to axial movement only relatively to another slab.

2

It has also been found that for maximum efficiency the load bearing members or dowel structures should be so constructed and arranged as to be balanced on opposite sides of the joint and that the dowel portions spanning the joint should have a maximum load bearing and transferring capacity vertically through the dowel.

It is a primary object of the invention, therefore, to provide dowel means for concrete expansion joints and the like which satisfy the above noted requirements in providing load transfer connections of maximum strength and efficiency.

An object of the present invention, therefore, is to provide improved means for producing joints in concrete roads and the like, utilizing dual dowel means in association with dual supporting shear plates, in which friction with respect to the surrounding concrete is reduced to a minimum by the novel bridging structure of balanced down and bearing members.

Another object is to provide, in such joints, means to eliminate tension in the concrete itself and to confine such tension directly and uniformly to the dowel and shear plate means constituting the load transfer elements extending in balanced relation between the respective slabs.

A still further object is to provide a dual dowel assembly concrete slab in a joint installation for transferring vertical load strain to the dowel means at the joint by the employment of cooperating dual shear plates associated with the concrete slabs and dowels.

A further object of the invention is the provision of dowel means for concrete expansion joints including a dowel and dowel shear plate and socket arranged for rigid connection with each slab adjacent a joint therebetween with provision for each dowel to telescopically engage within a socket in the expansion and contraction of the joint.

A still further object of the invention is the provision of a dowel unit for use in concrete expansion joints comprising a pair of shear plates, each having a dowel and dowel socket rigid therewith, each shear plate having an aperture for confining the dowel of the other shear plate to axial movement in expansion or contraction of the connected concrete slabs, and each shear plate having means rigid therewith for transmitting strains remote from the joint directly to the shear plate.

A still further object of the invention is the provision of dowel means of the above noted character, wherein the shear plates are retained for contact with an expansion joint strip during pouring of concrete in the formation of slabs thereof.

A still further object of the invention is the provision of dowel means for concrete expansion

joints including elements for cooperation at opposite sides of the joint and which elements are of like construction whereby manufacture and the setting up of the dowel means is simplified to a notable extent.

A still further object of the invention is the provision of dowel means for concrete expansion joints wherein the joint is greatly strengthened and balanced at each side thereof.

With the above and other objects in view, which will become more fully apparent as the nature of the invention is better understood, the same consists in the novel features of construction, combination and arrangement of parts as will be hereinafter more fully described, illustrated and claimed in the accompanying drawings.

In the drawings, wherein like characters of reference denote corresponding parts in related views:

Figure 1 is a perspective view disclosing a pair of cooperating shear plates, each provided with a dowel, the plates being in separated and aligned relation with the dowels positioned for entry through an opening in an expansion joint strip thence into an aligned socket in the opposed shear plate;

Fig. 2 is a top plan view, partially in section, of the structure of Fig. 1 in assembled position;

Fig. 3 is a vertical longitudinal section, showing the structure of Fig. 1 operatively positioned adjacent the joint between a pair of concrete slabs;

Fig. 4 is a perspective view similar to Fig. 1 showing modified forms of shear plates and dowels;

Fig. 5 is a perspective view showing the separated elements of Fig. 4 in assembled position;

Fig. 6 is a diagrammatic view in side elevation showing the effectiveness of the structure of Figs. 4 and 5 at the joint between a pair of concrete slabs;

Fig. 7 is also a diagrammatic view showing the well-known "jack-knifing" of the concrete slab joints in the absence of effective load transferring and reinforcing means;

Fig. 8 is a sectional perspective view disclosing a further embodiment of the invention;

Fig. 9 is an enlarged transverse sectional view substantially in the plane of line 9—9, Fig. 8;

Fig. 10 is a perspective view of a still further embodiment of the invention;

Fig. 11 is a horizontal sectional view on a reduced scale, as observed in the plane of line 11—11, Fig. 10;

Fig. 12 is a perspective view of a still further embodiment of the invention;

Fig. 13 is a perspective view of a still further embodiment of the invention; and

Fig. 14 is a sectional perspective view disclosing a still further embodiment of the invention.

Referring now in detail to the drawings, and first to Figs. 1 to 3, wherein is disclosed a dual dowel reinforcing and load transferring structure for use at the joints of concrete slabs and which structure is symbolic of all the modifications disclosed, the structure, as shown includes a pair of cooperating unitary elements 10 which are of like construction and are interchangeable in the slabs at the joint.

Each such element 10 comprises a shear plate 11, which as shown is rectangular but which may well be of other form and each shear plate is provided with a rectangular aperture 12 preferably located centrally thereof. A bar 13, which is preferably rectangular in cross section and of substantially greater vertical width or height than

horizontal thickness extends through the aperture 12 in each plate 11 at one side thereof and is rigidly secured to the plate as by welding, indicated at 14.

Each bar 13 includes a relatively long end portion 15 for projection into the body of the concrete slab remote from the shear plate and joint, as shown in Fig. 3, and an opposite end portion which constitutes the dowel portion 16.

The apertures 12 are of a transverse width equal to double the thickness of the respective bars 13 such that when the elements 10 are operatively positioned an aperture of the size of each dowel 16 will be provided in each plate 11 adjacent the bar 13 which is rigidly secured thereto. The dowel portions 16 will thus lap each other when assembled and slide into the respective apertures 12 upon moving the shear plates 11 into operative positions, as in Figs. 2 and 3.

A dowel socket or housing 17 must be provided in each concrete slab for slidably receiving each dowel 16 and such socket is preferably formed by means of a sheet of thin metal bent into rectangular form and one side having its opposed edges welded as at 18 to the top and bottom faces of the bar 13. As best shown at the extreme left of Fig. 1 the vertical web of the sheet metal housing is of greater length than the top and bottom faces so as to be bent therebetween and welded as at 19 into engagement with the bar 13. These sockets or housings 17 are therefore closed except for the dowel entrance 12 in the shear plate whereby admission of concrete is avoided for free relative sliding of the dowels 16 during expansion or contraction of the concrete slabs S (Fig. 3).

The usual expansion joint sealing strip 22 is provided with a rectangular opening 23 adjacent each plate and dowel structure for receiving the relatively slidable dowels 16 as is clearly indicated in Figs. 2 and 3.

The rear end of the bar portions 15 extend well into the concrete slabs S at opposite sides of the joint between two slabs and function to anchor the dowels and distribute the stresses therein and to transmit strains remote from the joint directly to the shear plates in the opposed faces of the slabs.

The dual dowel structure herein disclosed is highly efficient for this purpose and overcomes the ineffectiveness of dowel structures heretofore used or proposed. It is here to be particularly noted that while each dowel 16 is freely movable in the socket 17 of the cooperating dowel, said dowels are rigidly supported by its respective shear plate 11.

The dowels are positioned flatwise against each other or in laterally-contacting relation to mutually support each other when the slabs contract or expand. Under this condition the dowels will slide in opposing directions, each dowel bearing on the shear plate of the other dowel, and the pair of dowels cooperating to form a double truss spanning the joint at required intervals between the concrete slabs.

As disclosed, the present structure provides a pair of unitary rigid elements each embodying an anchoring portion, a shear plate, a dowel, and a dowel receiving socket, and each said element will be rigidly embedded in an edge or end face of a concrete slab as indicated in Fig. 3. Thus, the coaction of both elements or units, which may be identical, will result in the most efficient and rigid form of doweling, and one which will prevent jack-knifing of the slab as indicated diagrammatically in Fig. 7, with ample provision however for the free longitudinal movement of

the dowels within the sockets and within the shear plates to permit the slabs to expand or to contract.

It is further to be noted that by the improved structure herein disclosed a balanced effect is provided on both slab ends of and adjacent a joint therebetween which is necessary for continued operation of a dowel as a supporting element and for the efficient action herein described. This is not found in other structures of this general character heretofore used or proposed.

Referring now to Figs. 4 and 5 wherein is illustrated a structure similar to that of Figs. 1, 2 and 3, the shear plates 11^a are provided with upper and lower flanges 25 and 26 for anchorage in the concrete slabs whereby holding the shear plates effectively in position. Their upper flanges 25 are preferably provided with openings 27 to permit concrete to flow about the structure and honeycombing of the plastic material. The openings 27 further function to more firmly unite the flanges with the concrete. The bar portions 15^a in this embodiment are provided with laterally deflected rear end portions 28 for the purpose of greater anchorage in the concrete body of a slab as well as stress-relieving.

In the embodiment of the invention the bar portions 15^a are provided with openings 29 for receiving a wire support 30. The support may comprise opposed portions 31 each having a linear subgrade engaging portion provided with an angle portion 32 to permit contraction and expansion of the slabs. The support is primarily adapted to maintain the structure above the sub-grade and when it is desired to elevate the structure to a higher position, the portions 31 are brought closer and when it is desired to lower the structure, the portions 31 are spread apart. In this manner the assembly may be supported in a variable position above the sub-grade. Otherwise the structure is the same as that of Figs. 1 to 3 and functions in substantially the same cooperative manner.

In Fig. 6 is diagrammatically illustrated the structure of Figs. 4 and 5 in operative association with a concrete slab joint, but it is, however, to be understood that the dual dowel structures of the other embodiments of the invention will provide substantially the same efficiency. The slabs S as indicated are maintained in alignment when the improved plate and dowel structure are incorporated in the joint due to the long strain transmitting bar portions 15^a, the dual truss dowels, and the balanced support at each side of the joint.

When, however, ordinary structures of a dowel and socket embedded in the opposed end of the slabs is utilized at the joint, as heretofore proposed, insufficient support and balanced relation is provided so that the slabs S will jack-knife as indicated in Fig. 7 and thereafter prevent operation of the parts as a supporting bridge.

A further embodiment of the invention is illustrated in Figs. 8 and 9 which show the same general organization as previously described. The shear plates 11^b are provided with upper and lower right angular flanges 35 and 36 respectively, and the upper flanges 35 are each provided with an aperture 37. In this embodiment the usual expansion joint strip 22 is supported or held with its openings 23 in registration with the aperture 12 by a removable cap strip 38 which is of inverted U-shape. This cap strip as shown is provided with prongs 39 in registry with the apertures 37 and for entering same as indicated. This also temporarily prevents separation of the shear

plates from the strip 22 after setting up of the parts.

In this embodiment the bar portions 15^b are provided with downwardly projecting supports 40 for engagement with the sub-grade. Such supports are of a length to support the joint strip 22 on the sub-grade, or if desired in a suspended position. The cap strip 38 is removed prior to the final finishing of the concrete slabs. A wire spring member 41 may extend between the supports 40 to aid in holding the shear plates against the joint strip. However, when the cap strip 38 is used, such spring member may be omitted. The bar portions 15^b may further be provided with upwardly diverted anchorage portions 42 for better uniting the bars with the concrete slabs.

A further embodiment of the invention is illustrated in Figs. 10 and 11, wherein the shear plates 11^c are each provided with a pair of adjacent horizontally spaced vertically elongated apertures 44 and 45, and the bars providing the dowels 16 are each formed into a U-shaped concrete anchorage portion 46. One leg of each U-shaped portion 46 is extended to provide the dowel which extends forwardly through the aperture 44, and the other leg terminates at the rear side of the shear plate laterally of but adjacent the aperture 45. These legs of the U-shaped flat bar portions 46 are secured to the shear plates as by welding at the point of contact therewith as at 47 and 48. Cover plates 49 and 50 may be secured as by welding or otherwise to the upper and lower edges of the U-shaped bar portions 46 so as to form enclosed pockets, as indicated at the left in Fig. 10, thereby providing unobstructed dowel receiving sockets 17^a.

A further embodiment of the invention is illustrated in Fig. 12 which, as in all embodiments, comprises shear plates 11^d each having rigidly secured thereto in horizontally spaced relation a dowel 16^a and a dowel socket 17^b. Each shear plate of this embodiment is provided with an integral laterally and inwardly directed flange which seats on the sub-grade and which is returned upon itself in the form of a second superposed flange 53. A relatively fixed base is thus provided which extends up into the concrete slab with which the plate is associated. The shear plates are provided with anchoring and strain transmitting members 54 which extend upwardly in continuation of the dowels 16^a. The upper edges of the shear plates are provided with flanges 55 which are ribbed as at 56 for stiffening the flange and providing better anchorage in the concrete slabs. The shear plates may further be provided with reinforcing and anchoring ribs 57 between the flanges.

A further embodiment of the invention is illustrated in Fig. 13 which is substantially of the form of Figs. 1 to 3 but wherein the bars are of I-beam form or construction. In this embodiment, the shear plates 11^e are each provided with a relatively large centrally disposed rectangular aperture 59 through which extends an I-beam shaped bar 60 welded to the plate at the margin of the aperture as at 61. The width of the apertures provides for sliding contact between adjacent flanges of the bars in movement of the dowels 16^b through the apertures and into the sockets 17. These shear plates 11^e are shown provided with upper and lower flanges 62 and 63, each of which is further provided with an angularly disposed anchoring tongue 64. The flanges 62 and 63 are

7 preferably provided with apertures 55 to prevent honey-combing of the concrete when poured.

A still further embodiment of the invention is illustrated in Fig. 14 wherein the shear plates 14 are provided with flanges 67 and 68, and each plate has rigidly secured thereto a dowel 16 and a socket 17. In this embodiment the dowel bars in their concrete anchorage portions are of substantially horizontally V-form, each embodying a portion 69 as an extension of the dowel 16 and a downwardly diverted portion 70 having a curved end 71 thereof engaged through an aperture 72 in the vertical flange of an L-iron bar 73. The bars 73 are secured to the sub-grade by means of pins 74 having upper ends 75 hooked over the vertical flanges of the L-iron bars. This embodiment is quite similar to that of Fig. 12 but includes further the members 70 to 75 for retaining the shear plates in operative position.

While several embodiments of the invention are herein disclosed, it is to be particularly noted that the same general principle is common to all. The modifications are in fact only illustrative of the different forms that the shear plates may take, as well as the relationship of the dowels to each other, the means for preventing separation of the shear plates and dowels during pouring of concrete in the formation of the slabs, and means for firmly bonding the elements with the concrete and for transmitting strains from points distant from the plates or expansion joint to the plates with which the dowels are rigidly connected.

In all of the embodiments disclosed, however, each load transmitting unit comprises a pair of shear plates to be embedded in adjacent end faces of the concrete slabs as is clearly shown in Fig. 3, and each shear plate has rigidly connected therewith and extending therethrough, a bar member, a portion of which provides a dowel and another and longer portion provides for firmly bonding the shear plates with the slab and for transmitting strains from points distant from the joint to the shear plates.

Thus it will be observed that the shear plates when embedded in and firmly bonded with the slabs as disclosed there is no tendency or even possibility of the dowels having any movement transverse of their axes relative to the slabs with which they are united. Furthermore, the novel structure is such that in use the dowels cannot have lateral movement independently of each other or with the slabs with which they are relatively lengthwise movable, for the reason that the apertures 12, 45 and 59 in the various shear plates are of a vertical dimension so as to provide a close sliding fit with the upper and lower edges of the dowels.

Thus, upon consideration of Figs. 1 to 3, which is illustrative of all the forms so far as the principle of operation is concerned, it will be noted that each dowel 16 is rigidly supported by the shear plate in one slab S and is confined by the aperture 12 in the opposed shear plate 11 to horizontal or axial movement. Thus the two dowels 16 provide a rigid load transmitting truss between the opposed edges of the slabs S.

In all forms disclosed, the bars and dowels have substantial vertical depth for maximum load transmitting properties and such bars and dowels are disposed substantially distant from the top surface of the slabs as to avoid an otherwise possibility of cracking thereof.

In the embodiments of Figs. 1 to 9 and 13 the dowels are disclosed as being disposed in side face

contact while in Figs. 10, 11, 12 and 14 the dowels are horizontally spaced from each other a slight distance. In all cases, however, each unit embodies a pair of dowels which span the joint between adjacent edges of the slabs, the dowels being confined to axial movement relative to the opposing slabs while ample provision is made for relative axial movement of the dowels and slabs for expansion and contraction of the joint.

Each unit in each embodiment of the structure disclosed comprises a pair of substantially identical members, as 10 in Fig. 1, which not only simplifies manufacture but also materially expedites assembly in that it is not necessary to select left and right members, as is the case with prior structures of this general character. Furthermore, the members are relatively simple in construction and can all be formed from bar and sheet material.

From the above description, it is believed that 20 the features and advantages of the invention will be readily apparent to those skilled in the art, and it will of course be understood that changes in the form, proportion and minor details of construction may be resorted to without departing 25 from the spirit of the invention and scope of the appended claims.

What I claim and desire to secure by U. S. Letters Patent is:

- Load transfer means for an expansion joint connecting opposed edges of concrete slabs and an interposed apertured expansion strip, said load transfer means comprising a shear plate for engagement with each side of said strip, a dowel rigidly supported by each plate for projection through the aperture in said strip, each plate having an aperture for slidably receiving the dowel of the other plate in the expansion or contraction of the joint, each dowel comprising the forward end of a bar extending through a second aperture in the supporting plate, the bar rearwardly of the plate being bent in the provision of a U-shaped portion with the free end of the bar engaged with the shear plate and rigidly secured thereto, said shear plates being of sufficiently heavy gauge to slidably sustain said dowels and prevent spalling of the slab thereabout and said dowel-receiving apertures being disposed between the opposed legs of the U-shaped portions.
- The combination set forth in claim 1 together with closure plates rigidly secured to the upper and lower edges of said U-shaped portion in the provision of a dowel-receiving socket and strain-transmitting member for embodiment in the concrete slabs.

JOHN N. HELTZEL.
